UNITED STATES PATENT OFFICE.

JESSE J. HEAP, OF NEW YORK, N. Y., ASSIGNOR TO UNION SPECIAL MACHINE COMPANY,
OF CHICAGO, ILLINOIS, A CORPORATION OF ILLINOIS.

FOLDER FOR SEWING-MACHINES.

1,308,631.

Specification of Letters Patent.

Patented July 1, 1919.

Application filed November 8, 1918. Serial No. 261,648.

To all whom it may concern:

Be it known that I, JESSE J. HEAP, a citizen of the United States, residing at New York city, in the county of Kings, State of New York, have invented certain new and useful Improvements in Folders for Sewing-Machines, of which the following is a description, reference being had to the accompanying drawing and to the figures of reference marked thereon.

The invention relates to new and useful improvements in folders for sewing machines, and more particularly to a folder for forming a double lap seam fold.

An object of the invention is to provide a folder of the above character with means for guiding the upper ply of fabric, turning underneath the edge of said upper ply of fabric and for forming a reentrant fold in said upper ply of fabric back from the edge thereof, so as to give to the seam an appearance of having been covered by a tape.

In the drawings which show by way of illustration one embodiment of the invention—

Figure 1 is a front view of a folder embodying my improvements;

Fig. 2 is a rear view of the same;

Fig. 3 is a view, more or less diagrammatically, of a section on the line 3—3 of Fig. 4;

Fig. 4 is a plan view of the folder;

Fig. 5 is a view showing more or less diagrammatically two fabric sections as having entered the folder;

Fig. 6 is a view showing more or less diagrammatically the folds in the fabric sections and the relation of the lines of stitches thereto;

Fig. 7 is a top perspective view of a seam made on my folder.

My improved folder consists of a base plate having an upwardly extending curved guiding wall which supports a guiding plate which is shaped so as to receive and fold the edge of an upper ply of fabric and also form a reentrant fold in the upper ply of fabric back from the edge thereof. The upwardly projecting wall carries a plate with a recess which co-operates with the extreme edge of the guiding plate in the forming of this reentrant fold.

The invention will be more clearly understood by a detail reference to the figures

in the drawings. My folder, as illustrated, 55 consists of a supporting base 1, having an upwardly projecting curved wall 2. Said wall curves to the left, as viewed in Fig. 1, so as to form a guiding recess 3 for the fabric section F'. This guiding recess is 60 shaped so as to fold the edge of an under ply of fabric. While I prefer to fold the other edge of fabric, it will be understood that, from certain aspects of the invention, the edge of the under ply of fabric may 65 lie straight and unfolded, as this edge is on the wrong side of the seam, and when the edge is unfolded then the wall will be straight rather than curved.

At the extreme upper edge of this wall 2 70 is a supporting bar 4, and mounted on the supporting bar 4 is a curved guiding plate 5. Said plate extends outwardly from the bar 4, thence upwardly, thence over the bar, thence downwardly and thence inwardly 75 to a free edge 6. Secured to the bar 4 is a plate 7 and said plate, together with the bar and guiding wall 2, are formed with a recess 8 which is directly opposite the free edge 6 of the folder. The bar 4 is also 80 formed with a recess 9, which receives the edge of the upper ply of fabric and guides the same. The fabric section directed by the curved guiding plate 5 is indicated at F in the drawings. As the fabric sections 85 enter the folder the lower fabric section has its edge turned up, as indicated at 10 in Fig. 5, while the upper fabric section has its extreme edge turned downwardly and inwardly, as indicated at 11. The upper section F is also folded back as at 12, to form a reentrant fold. In Figs. 6 and 7 of the drawings, I have shown the completed seam. This reentrant fold gives to the seam an appearance of having a tape applied thereto. 95 Said tape is indicated at T in Figs. 6 and 7 of the drawings.

The fabric sections are joined by two parallel lines of stitches, indicated at 13 and 14. The line of stitches 14 passes through 100 both fabric sections and secures the folded in edge 11 of the fabric section F. The line of stitches 13 passes through the reentrant fold and the folded over edge 10 of the under fabric section. It is understood, of 105 course, that the fabric sections, after they are properly folded and placed relative to each other, pass directly from the folder to

the stitching mechanism, which consists of a pair of needles arranged for forming two parallel lines of stitches.

The details of construction of the folder 5 may be varied, the essential feature consisting in the guiding of the upper section of the fabric in such a way as to fold its extreme edge and form a reentrant fold back from the edge, so as to give the appearance 10 of the seam having been covered by a tape.

Having thus described my invention, what I claim as new and desire to secure by Letters Patent, is:

1. A folder for sewing machines comprising a base plate, a curved guiding plate carried thereby and supported so that the edge of an under fabric section may be directed beneath said curved guiding plate, said curved guiding plate being shaped so as to 15 fold the edge of an upper fabric section and form a reentrant fold therein back from the folded edge, whereby the seam will have the appearance of having been covered by a tape.

2. A folder for sewing machines comprising a base plate having a vertically extending wall, devices carried thereby having a recess for receiving a reentrant fold in the upper section of fabric, a curved plate carried by the wall and extending upwardly 20 and over the wall and having its free edge

disposed relative to said recess, so that an upper section of fabric guided by said curved plate will have its free edge folded underneath and a reentrant fold formed in 35 said fabric section back from its edge to give said fabric section the appearance of having a tape applied thereto.

3. A folder for sewing machines comprising a base plate having a vertically extending wall, devices carried thereby having a recess for receiving a reentrant fold in the upper section of the fabric, a curved plate carried by the wall and extending upwardly 40 and over the wall and having its free edge 45 disposed relative to said recess, so that an upper section of fabric guided by said curved plate will have its free edge folded underneath and a reentrant fold formed in 50 said fabric section back from its edge to give said fabric section the appearance of having a tape applied thereto, said vertical wall and devices supported thereby being shaped so as to fold over the edge of the lower section 55 of fabric.

In testimony whereof, I affix my signature, in the presence of two witnesses.

JESSE J. HEAP.
